(57) **CLAIM**

The ornamental design for the golf club head, as shown and described.

DESCRIPTION

FIG. 1 is a front isometric view of a golf club head showing my new design;

FIG. 2 is an enlarged top isometric view of the golf club head of FIG. 1;

FIG. 3 is a rear elevational view of the golf club head of FIG. 2;

FIG. 4 is a front elevational view of the golf club head of FIG. 2;

FIG. 5 is a right side elevational view of the golf club head of FIG. 2;

FIG. 6 is left side elevational view of the golf club head of FIG. 2;

FIG. 7 is top plan view of the golf club head of FIG. 2;

FIG. 8 is a bottom plan view of the golf club head of FIG. 2; and,

FIG. 9 is a cross-sectional view taken on line 9-9 of the golf club head of FIG. 4.

The features shown in broken lines in the drawing depict portions of the design that form no part of the claimed design.
